CLAIM

The ornamental design for a cover, as shown and described.

DESCRIPTION

FIG. 1 is a first top perspective view of a cover, according to our new design;

FIG. 2 is a first bottom perspective view of the cover;

FIG. 3 is a second top perspective view of the cover;

FIG. 4 is a second bottom perspective view of the cover;

FIG. 5 is a front side elevational view of the cover;

FIG. 6 is a rear side elevational view of the cover;

FIG. 7 is a right side elevational view of the cover;

FIG. 8 is a left side elevational view of the cover;

FIG. 9 is a top plan view of the cover;

FIG. 10 is a bottom plan view of the cover; and,

FIG. 11 is a third top perspective view of the cover shown in environmental use, the door being omitted for ease of illustration.

The dash-dash broken lines represent environmental structure and form no part of the claimed design. The dot-dash broken lines define the bounds of the claimed design and form no part thereof. In addition, all interior portions of the cover, visible in FIGS. 2, 4, and 10, form no part of the claimed design.

1 Claim, 11 Drawing Sheets
